SPECTACLE FRAME FRONT

Marcel Arnaut, Paris, France, assignor to Societe Industrielle de Lunetterie, Paris, France

Application April 10, 1956, Serial No. 41,000

Claims priority, application France December 21, 1955

Term of patent 7 years

(Cl. D57—1)

Fig. 1

Fig. 2

Fig. 1 is a front elevational view of a spectacle frame front embodying my new design; and

Fig. 2 is a top plan view thereof.

The dominant feature of my design resides in the portions shown in full lines.

I claim:

The ornamental design for a spectacle frame front, as shown and described.
